UNITED STATES PATENT OFFICE.

FRANKLIN PIERCE CAUBLE, OF HIGH POINT, NORTH CAROLINA.

CLOCK-OPERATED ELECTRIC SWITCH.

1,026,905.

Specification of Letters Patent.

Patented May 21, 1912.

Application filed March 2, 1912. Serial No. 681,151.

To all whom it may concern:

Be it known that I, FRANKLIN P. CAUBLE, a citizen of the United States, and a resident of High Point, county of Guilford, State of North Carolina, have invented certain new and useful Improvements in Clock-Operated Electric Switches, of which the following is a full and clear specification, reference being had to the accompanying drawings, in which—

Figure 1 is a plan view; and Fig. 2 a side elevation of my apparatus.

The object of this invention is to provide a simple apparatus whereby an ordinary alarm clock can be utilized to automatically, at any predetermined time within the limits of the apparatus open or close an electric light or other circuit, as more fully hereinafter set forth.

In the drawing, *a* designates the usual gong hammer of a well known form of alarm clock, which hammer is adapted to be rapidly vibrated when the alarm is set off by the clock. This clock is attached to a base board *b* in any suitable manner, and attached to the hammer is a wire or cord *c* which is carried down to the base board and under a guide loop or roller *d* thereon, the extremity of this wire or cord *c* being attached to the under side of a trigger *e* pivoted at its forward end to the base board and provided at the same end with a projection *f*.

A wire bail *g* is pivoted on a pivot extending across the board just in front of the trigger *e*, and attached to the free end of this bail is a wire or cord *h*, which extends upwardly and passes over an elevated pulley *i* and thence downwardly and forwardly to the switch lever *j* in the electric circuit. A coil spring *k* surrounds the pivot of this

bail and tends to swing it strongly backward, toward the clock, and when thus swung over, as shown in dotted lines in Fig. 2, the cord or cable *h* will be drawn taut 45 and the switch lever *j* will be swung upwardly to an open position. To lock the bail in its abnormal or operative position, I employ a pivoted lever *l* whose free end is adapted to engage under the lip *f* of the 50 trigger and be thereby held down, thus holding the bail down close to the base board, in its operative position.

It will be observed that with the parts in the position shown in full lines in Fig. 2, 55 when the alarm hammer is vibrated, the cord *c* will trip the lever *e* and thus release lever *l*, whereupon the spring *k* will with considerable force and very quickly throw the bail *g* over backwardly to the position 60 shown in dotted lines, which action will snap open the switch.

Having thus described my invention, what I claim as new, and desire to secure by Letters Patent, is—

In combination with an alarm clock embodying a vibratory alarm lever, a cord connected at one end to said lever, a trigger connected to the other end of said cord, a lock lever adapted to be held down by said trigger, a spring actuated swinging bail adapted to be held in abnormal position by said lock lever, a cord connected to said bail and a switch device adapted to be operated 70 by a pull on this latter cord. 75

In testimony whereof I hereunto affix my signature in the presence of two witnesses.

FRANKLIN PIERCE CAUBLE.

Witnesses:

S. H. HILLIARD,
ED. L. RAGAN.
